UNITED STATES PATENT OFFICE.

WILLIAM M. WHEILDON, OF ASHLAND, MASSACHUSETTS, ASSIGNOR TO EDWARD H. ANGIER, OF FRAMINGHAM, MASSACHUSETTS.

PAPER-CRINKLING APPARATUS.

1,383,360.

Specification of Letters Patent.

Patented July 5, 1921.

Application filed August 6, 1920. Serial No. 401,743.

To all whom it may concern:

Be it known that I, WILLIAM M. WHEILDON, a citizen of the United States, and a resident of Ashland, in the county of Middlesex and State of Massachusetts, have invented an Improvement in Paper-Crinkling Apparatus, of which the following description, in connection with the accompanying drawings, is a specification, like characters on the drawings representing like parts.

This invention relates to the manufacture of crinkled paper, and the purpose is to provide means for effecting with certainty a pronounced crinkling or craping.

15 The invention may best be understood by the following description taken in connection with the accompanying drawing illustrating diagrammatically a form of paper-crinkling machine having my improvements applied thereto and wherein:

Figure 1 is a longitudinal section; and Fig. 2 is a broken plan of the craping roll and adjacent parts from the direction of the arrow 2 in Fig. 1.

25 In the drawing I have illustrated a machine which is adapted to crape or crinkle finished paper, the paper web 5 being drawn from a suitable supply roll and passed through a saturating bath 7 which may, if desired, be heated as by the steam pipes 9. The paper passes from the saturating bath under squeeze rolls 11 and 13, over a smooth-surfaced crinkling roll 15 which carries it against the edge of a doctor blade 17. This 30 doctor blade crowds back the wet paper on itself and removes it from the roll 15 in the form of a craped or crinkled web, as shown at the right hand in the figure, which web is carried away by a conveyor 19. This type of 35 machine as so far described is well known in the art and for further explanation of the principles involved I may refer to the patents to Arkell Nos. 790,021 and 790,022, dated May 16, 1905.

40 45 The crinkling, whether prepared by the wet process as here shown or otherwise, may be most effectively carried out if the paper web is in close contact with the crinkling roll 15. Herein I have illustrated the use 50 of fluid pressure means for securing close adherence of the web to the roll 15 until shortly before it reaches the doctor blade 17 and in particular I have illustrated both positive and negative fluid pressure means 55 as utilized together. For example, a suit-

able blast may be applied to the paper on the roll 15 just before it reaches the doctor blade 17 and I have herein illustrated a pipe 21 extending parallel to the surface of the roll and having a port 23 through which air may be blown against the paper to hold it down on the roll, the air being supplied by a suitable blower 25. The pipe is preferably supported to swing about an axis alined with the axis of the roll as best shown in Fig. 2 so that it may be adjusted to desired angular position thereabout and a slip joint 27 may be provided to permit adjustment of the pipe relative to the surface of the roll itself.

To facilitate the adherence of the paper to the roll 15 I preferably provide suitable shallow grooves 29 in the surface of the latter permitting air to escape from beneath the paper so that the latter may be pressed closely into contact with the roll. I have herein shown these grooves as circumferential. Further to provide for such escape the craping roll 15 may be hollow and may be provided with perforations 31, preferably at the bottom of the grooves, to permit air to escape from beneath the paper through the interior of the roll.

In the present example of the invention I also utilize these perforations 31 for sucking the air from beneath the paper so that it is held to the craping roll both by pressure from the blast pipe 21 and by suction. This suction is applied through a suitable restricted zone adjacent the doctor blade 17 and opposite the blast pipe 21 and I have herein shown a substantially wedge shaped air box 35 having an open base presented to the interior of the hollow roll 15 and therefore opposing a certain number of the openings 31. This wedge shaped air box 35 may be mounted to swing about the axis of the roll to permit adjustment and may be positioned by any suitable means herein diagrammatically illustrated by the rotatable connection 37 between the axial nozzle section 39 carried by box 35 and the pipe 41 leading to a suitable exhaust 43.

Having thus described in detail the particular form of my invention shown by way of example in the accompanying drawings, what I claim is new and desire to secure by Letters Patent I shall express in the following claims.

Claims:

1. Paper crinkling mechanism comprising

a paper-receiving roll and a coöperating crinkling element in combination with means for directing a blast against the roll to hold the paper thereagainst as it advances to said element, the roll having grooves to permit the escape of air from beneath the paper.

2. Paper crinkling mechanism comprising a paper-receiving roll and a coöperating crinkling element in combination with means for directing a blast against the roll to hold the paper thereagainst as it advances to said element, the roll having perforations thereby to permit air to be discharged from beneath the paper through the interior of the roll.

3. Paper crinkling mechanism comprising a paper-receiving roll and a coöperating crinkling element in combination with means for directing a blast against the roll to hold the paper thereagainst as it advances to said element, the roll having grooves and perforations at the bottom of the grooves through which air may escape from beneath the paper.

4. Paper crinkling mechanism comprising

a perforated paper-receiving roll and a coöperating crinkling element in combination with means for blowing air against the paper on the roll as it advances to the crinkling element and coöperating means for sucking air from beneath the paper in a zone slightly in advance of the position of said element.

5. Paper crinkling mechanism comprising in combination a paper-receiving roll and a coöperating crinkling element and combined positive and negative fluid pressure means for holding the paper to the roll in a zone in advance of the position of said element.

6. Paper crinkling mechanism comprising a paper-receiving roll and a coöperating crinkling element in combination with means for directing a blast against the roll to hold the paper thereagainst as it advances to said element and means permitting the discharge of air from between the paper and the roll.

In testimony whereof, I have signed my name to this specification.

WILLIAM M. WHEILDON
